UNITED STATES PATENT OFFICE

153,323

DESIGN FOR A RADIO CABINET

Wallace Schier, Forest Hills, Long Island, and
David L. Doggett, Mount Kisco, N. Y., assignors
to Federal Telephone and Radio Corporation,
New York, N. Y., a corporation of Delaware

Application January 11, 1947, Serial No. 136,074

Term of patent 14 years

(Cl. D56—4)

To all whom it may concern:

Be it known that we, Wallace Schier and David L. Doggett, citizens of the United States, residing at 150 Greenway Terrace, Forest Hills, Long Island, New York, and Millwood Road, Mt. Kisco, New York, respectively, have invented a new, original, and ornamental Design for a Radio Cabinet, of which the following is a specification, reference being had to the accompanying drawings, forming part thereof.

Fig. 1 is a view in perspective showing the cabinet with the front panel exposed:

Fig. 2 is a view in plan of the cabinet shown in Fig. 1;

Fig. 3 is a view in perspective of the cabinet with the front panel hidden in the base of the cabinet;

Fig. 4 is a view in perspective of the rear side of the cabinet when the front panel is exposed as in Fig. 1; and

Fig. 5 is a view in perspective of the rear side when the front panel is hidden in the base as in Fig. 3.

The cabinet ordinarily appears as shown in Fig. 3, the cabinet being rotated 90 degrees in a rearward direction about a horizontal axis whereby the front panel is exposed as shown in Fig. 1.

The characteristic features of my design reside in the portions shown by means of full lines in the drawing.

We claim:

The ornamental design for a radio cabinet, substantially as shown and described.

WALLACE SCHIER.
DAVID L. DOGGETT.
